UNITED STATES PATENT OFFICE.

JESSE M. CURTICE, OF LOUISVILLE, KENTUCKY.

CHURN.

SPECIFICATION forming part of Letters Patent No. 427,053, dated May 6, 1890.

Application filed February 4, 1889. Serial No. 298,612. (No model.)

To all whom it may concern:

Be it known that I, JESSE M. CURTICE, a citizen of Louisville, in the county of Jefferson and State of Kentucky, have invented 5 certain new and useful Improvements in Churns; and I do hereby declare the following to be a full, clear, and exact description of the invention, such as will enable others skilled in the art to which it appertains to 10 make and use the same.

My invention relates to an improvement in churning, and more particularly to such as are known as "working-body" or "rocking" churning without dashers, and has for its object to produce a churn of this character which 15 shall be simple in construction, yet substantial, and one in which the operation shall be easy and effective.

A further object is to so construct the body 20 of the churn that it shall be supported at its ends, the supports being connected to the frame at points near the center of the churn-body, whereby an oscillatory and swinging motion is obtained.

25 A further object is to provide a churn in which the body shall be so mounted that it may have an oscillatory motion imparted to it, and that the contents of the churn in seeking its level will tend to maintain the body 30 horizontal, when the mechanism is at rest, without the aid of weights or similar devices.

A further object is to provide a churn in which the motion of the contents will assist in the operation of the churn, and in which 35 the leverage is so arranged that there will be no lost motion or power, and that only a small portion of the contents has to be raised at one time by the power, thereby making the operation very easy.

40 With these objects in view my invention consists in certain novel features of construction and peculiar combinations and arrangements of parts, as hereinafter set forth, and pointed out in the claims.

45 In the accompanying drawings, Figure 1 is a side elevation of the device. Fig. 2 is a vertical cross-section. Fig. 3 is a detached view of the band-wheel and attached parts. Fig. 4 is a detached plan view of the treadle. 50 Fig. 5 is a view of a modification of the treadle; and Fig. 6 is a view in side elevation,

partly in section, showing the manner of mounting the churn-body and treadles.

A represents a frame, comprising feet or base-supports *a a*, having secured thereto two 55 uprights or standards *b b'*, a cross-piece *c* being secured between said standards near their base. The base-supports *a* and standards *b b'* are provided with perforations to align with the longitudinal grooves *c'*, made in the edges 60 of the cross-piece *c*. Metal rods *c*² are passed through these grooves and perforations and provided at one end with heads and at the other end with suitable nuts, by means of which rods the lower portion of the frame is 65 securely held together.

Placed between the uprights *b b'* above the cross-piece *c* is a bar *d*, having grooves in its edges for the reception of rods *d'*, which latter pass through perforations in the standards 70 *b b'*, and are provided with heads on one end and nuts on the other. A metal plate or bracket *B* is inserted between one end of the bar *d* and the standard *b'*, having notches *d*² in the top and bottom for the accommodation 75 of the rods *d'*. The portions of the plate which bear against the side faces of the bar *d* are furnished with notches *e*, and in line with these notches a perforation is made through said bar for the reception of a pin *e'*, 80 which projects beyond both sides of the bar *d*, and upon which the treadles *C* are mounted. The treadles *C* are notched at one corner for the accommodation of bosses *f*, having recesses *f'*, which project from the plate or 85 bracket *B*. Secured to the inner edge of each treadle is a plate *f*², adapted to project into the notches of the bosses *f*, said plates being provided with perforations to permit the passage of the pin *e'*. By this construction it 90 will be seen that the treadles will be permitted to have a free vibratory movement on their pintles, but prevented from a side or wobbling motion and consequent rattling of the treadles during the operation of the churn. 95

Secured to the top of standards *b b'* are brackets *g g'*, of any preferred design. The ends of four rods *D* are loosely connected with the brackets *g g'*, two to each bracket. The body *E* of the churn is provided on its bottom at or near each end with plates *h*, corresponding in number with the rods *D*, and 100

having lugs or ears thereon to produce notches h' . The free ends of the rods D are bent to produce square-cornered hooks h^2 , which are inserted in the notches h' of plates 5 h. Thus it will be seen that the body E is supported from the brackets $g\ g'$ by means of the rods D, and that said rods are connected with the churn-body at or near its ends.

A segment G, which may be semicircular, 10 as shown, or a complete wheel, if desired, is provided with a central perforated boss i for the reception of a shaft i' , upon which it is adapted to have an oscillatory motion, said shaft being fixed at one end in the standard 15 b near its top.

Projecting centrally from the broadened rim of the wheel G is a lug j. A strap of leather or other suitable material H is placed upon the band-wheel and its ends allowed 20 to hang downwardly from each side, a perforation being made in the strap for the reception of the lug j on the segment G. The strap H is furnished near its extremities with perforations k for the reception of the 25 upper hooked ends of two rods I. The lower ends of the rods I are passed loosely through perforations l, made in the front ends of the treadles; and nuts or washers are secured upon the lower extremities of said rods; or 30 the ends of the rods are bent to prevent them from pulling through the perforations in the treadles.

Projecting from the boss i of segment G is an arm J, bifurcated at its free lower end to 35 receive a headed rod l' on the churn-body E, said pin being located in the side face of the body centrally between its ends and near the bottom.

It will be seen that when the segment G is 40 turned on its shaft the forked arm will by its engagement with the rod l' cause the body to make a longitudinal movement and at the same time an oscillatory movement on its axis. When the body is thus tilted, the weight of its 45 contents will tend to bring it back to a level, and the flow of the contents will carry it beyond a horizontal position. The segment G is now oscillated in the reverse direction to that above described, and consequently the churn-body is moved and oscillated in the reverse direction. During the oscillation of the body 50 rod l' will describe about two-thirds of a circle and the churn-body will incline at an angle of about forty-eight degrees in opposite directions. Again, when the churn-body is tipped to the right nearly all the weight of the body and contents will be on one pair of the rods D; but enough will be to the left of where rods D are attached to the ends of the body to cause 55 the body to swing back to a level, and the momentum of the contents will cause the contents to rush beyond the center, thus helping to tip the body to the left, and so on during the operation of the churn. More than half 60 the contents are always resting on two of the four rods D, so that the arm J never has to

lift as much as half the weight of the contents of the body.

A handle M may be attached to any convenient part of the body, if desired.

In cases of very wide churning the treadle mechanism shown in Fig. 5 will be adopted. In this construction the treadles will be reduced to about one-half the width of the treadles shown in Figs. 1 and 3 and extended 75 to the front end of the churn-frame. Foot-plates L, provided with perforated ears m, are located at the free ends of the treadles and pivoted thereto by means of a bolt m', passing through said lugs and the treadles. 80 The rods I are attached to the plates L through perforated lugs n, projecting from the foot-plates L.

Slight changes might be made in the constructive details of my invention without departing from the spirit thereof or limiting its scope; hence I do not wish to limit myself to the precise details of construction herein set forth; but,

Having fully described my invention, what 90 I claim as new, and desire to secure by Letters Patent, is—

1. The combination, with a churn-body, a supporting-frame, and supporting-rods pivotally connecting the frame and churn-body, of 95 an arm pivotally mounted on the supporting-frame at a point above the bottom of the churn-body, a lug projecting from the churn-body below the pivotal point of the arm and engaging said arm, and a device for vibrat- 100 ing said arm.

2. The combination, with a frame, of treadles pivoted thereto, rods attached to said frame, a churn-body supported by said rods, a segment having a depending arm, a projection 105 on the churn-body engaged by said arm, a strap passing over the segment, and rods connecting the strap and treadle, substantially as set forth.

3. The combination, with a churn-body and 110 supporting-frame, of rods attached to said frame near the center of the churn-body and pivotally connected with said body at or near its ends, a segment having a depending arm loosely engaging the churn-body, a lug on the 115 rim of the segment, a strap passing over the segment and engaging the lug on the segment, treadles, and rods connecting the ends of the straps with the treadles, substantially as set forth.

4. The combination, with a churn-body and a supporting-frame, of supporting-rods pivotally connected at their outer ends to the ends of the churn-body and at their inner ends to the supporting-frame, a segment having a 125 forked arm, a rod on the body of the churn with which said arm engages, and mechanism for oscillating said segment, substantially as set forth.

5. The combination, with a frame, of a bar 130 secured between the uprights thereof, a plate held between one end of said bar and one of

the uprights, a pin passing through the bar and recesses in the plate, treadles mounted on said pin, a churn supported in the frame, and devices for connecting the churn-body and treadles, substantially as set forth.

6. The combination, with a frame, of a bar secured between the uprights thereof, a plate held between one end of said bar and one of the uprights, a pin passing through the bar and recesses in the plate, recessed bosses projecting from said plate, treadles, plates on said treadles projecting into the recessed

bosses and provided with perforations for the passage of the pin, a churn-body supported in the frame, and devices for connecting the churn-body and treadles, substantially as set forth. 15

In testimony whereof I have signed this specification in the presence of two subscribing witnesses.
